UNITED STATES PATENT OFFICE.

SAMUEL T. KRONENBERG, OF PITTSBURGH, PENNSYLVANIA, ASSIGNOR OF FIFTY-FIVE ONE-HUNDREDTHS TO JOHN C. WOLFRAM, OF PITTSBURGH, PENNSYLVANIA.

VEHICLE-WHEEL.

1,081,757.

Specification of Letters Patent. Patented Dec. 16, 1913.

Application filed March 12, 1912. Serial No. 683,292.

To all whom it may concern:

Be it known that I, SAMUEL T. KRONENBERG, a resident of Pittsburgh, in the county of Allegheny and State of Pennsylvania, have invented certain new and useful Improvements in Vehicle-Wheels, of which the following is a specification.

This invention relates to that type of wheels in which the body and the tread-carrying portions are movable relatively to each other, as when cushioning means is interposed between them, and the object is to provide new and efficient means for opposing such relative movement in circumferential direction.

The engaging parts of the wheel body and rim embody a magnet and a pole connecting armature, in the present adaptation the magnet being carried by the body with the rim constituting the armature, and with the faces of the magnet and the armature slidably engaging the magnet in such manner as not to interfere with the relative radial play due to the action of the cushioning means, but opposing relative circumferential movement, the magnetic force of pull increasing with the circumferential movement in such manner as to prevent undue displacement and thereby protect the interposed cushioning means from destructive strains.

In the accompanying drawings, Figure 1 is an elevation of a portion of a wheel constructed in accordance with the invention; part A of the wheel periphery of said view being in elevation and parts B, C, and D in section on lines B—B, C—C, and D—D, respectively, of Fig. 2. Fig. 2 is a vertical cross section on line 2—2, of Fig. 1. Fig. 3 is a detail of a portion of one of the pole-forming plates secured to the wheel, and Fig. 4 is a similar view of a portion of one of the material-forming plates of the tread-carrying rim. Fig. 5 is a section of the engaging face of the body and rim plates taken on line 5—5, of Fig. 2. Fig. 6 is a diagrammatic view illustrating engagement of the relatively movable magnet and armature-forming plates. Fig. 7 is a view similar to Fig. 1 illustrating another embodiment of the magnet, a portion of the periphery of the wheel being shown in section on line 7—7, of Fig. 8. Fig. 8 is a cross section on line 8—8, of Fig. 7.

55 Referring to the drawings and particu-

larly to Figs. 1 and 2, the wheel body may consist of a hub 2, rim or felly 3 of non-magnetic material, and interposed spokes 4. Secured to and projecting outwardly from felly 3 are the concentrically arranged plates 5 which comprise the opposite poles of a circular electro-magnet which may be energized by a series of coils 6 arranged between projections 5' on the inner periphery of the plates. Current may be supplied to the coils in any suitable manner. In the construction shown, the wheel is rotatable on spindle S, and secured to the wheel are the slip or contact rings 7 and 8, with the leads 7' and 8' connecting them, respectively, with opposite ends of coils 6. The current may be passed to rings by brushes 9 from any suitable source, as from a storage battery, or from the magneto with which most self-propelled vehicles are equipped. The tread-carrying rim is of channel form and consists of base 10 and the parallel inwardly extending side plates 11 which are entered between and slidably engage the pole-forming plates 5 of the wheel body. Plates 11 may be extended outwardly beyond channel base 10 to form the clencher elements 11' for confining a suitable tire or tread 12. The rim thus constructed constitutes an armature or keeper for the magnet. The cushioning means, located in the channel-like space between the wheel body and rim, may be variously constructed. In the embodiment here shown it consists of radially arranged springs 13, secured between non-magnetic band 14 secured to felly 3, and channel base 10, thereby providing the necessary insulation.

To obtain the desired action the magnet and armature elements must so coöperate as not to impede the relative radial movements of the parts, but must retard the circumferential movement. To accomplish this the engaging faces are divided into magnetic and non-magnetic sections, the magnetic sections of the opposed faces being normally in engagement and so disposed as to have full play one on the other in direction radially of the wheel, but play in the opposite direction results in the faces being separated and their magnetic force-transmitting areas so diminished as to set up a magnetic pull which increases as the areas diminish and stops the movement before there is destructive distortion of the cushioning mechanism.

In the present adaptation, the pole-forming plates 5 have their inner faces recessed to receive inserts 16 of babbitt, brass, graphite, or other non-magnetic material, these 5 inserts alternating with face portions 17 of the magnetic ring 5. Similarly, each of rim plates 11 has its engaging face provided with the non-magnetic portions 16' alternating with the ring face portions 17'.

10 The magnetic and non-magnetic face portions of the magnet and armature elements are disposed radially of the wheel and with like parts normally in register, as in Fig. 5. Relative movement of the wheel body, and 15 rim in radial direction causes magnetic face parts 17, 17' to slide longitudinally of each other without appreciably affecting their magnetic force-transmitting areas. But as said face parts are relatively narrow, independent 20 circumferential movement of either the wheel body or the rim results in moving the magnetic faces over the interposed non-magnetic material, somewhat as shown in Fig. 6, thereby immediately diminishing the 25 magnetic force-transmitting areas thereof, and as these areas diminish the magnetic pull increases with sufficient strength to preclude movement sufficient to cause damage. A range of movement is thus provided affording 30 sufficient flexibility circumferentially of the parts, but which limits the same within safe bounds. Lubricant may be admitted to the engaging surfaces through ducts 15' leading from oil channel 15. 35 When there is relative radial movement of the parts at the bottom and top of the wheel, due to distortion of the cushioning means under the weight of the load or from other cause, there is a simultaneous relative circumferential movement of the parts at the 40 sides of the wheel, and as such circumferential movement is opposed by the magnetic pull, as above described, the cushioning means is correspondingly stiffened and 45 strengthened.

In the embodiment of Figs. 7 and 8, a metallic wheel felly 3' is illustrated which comprises a core for the single wheel-encircling magnet coil 6' instead of the plurality 50 of coils of the first described construction, and in which adaptation it is of course necessary to provide only one set of leads 18, 18' to contact rings 7 and 8.

The current for energizing the magnets 55 may be obtained from various sources and may be variously conducted to the magnet coils. And while a wheel is here shown which rotates on its spindle or axle, it will be understood that the invention may be 60 applied to wheels without regard to the manner in which they are mounted.

I claim:—

1. The combination of a wheel body and a rim movable radially and circumferentially 65 relatively to each other, means for

cushioning the radial movement, and magnetic means for opposing the circumferential movement.

2. The combination of a wheel body, magnet poles on the body, a tread-carrying rim 70 movable radially and circumferentially of the body, the rim constituting an armature and having faces slidable on the magnet poles in direction circumferentially of the wheel, the engaging faces of the rim and pole, being formed to diminish their engagement as the parts move in circumferential direction from normal position, and means for cushioning the radial movement of the parts.

3. The combination of a wheel body, a magnet carried by the body and having two circular poles arranged concentrically with the body, a tread-carrying rim movable circumferentially of the body, the rim constituting an armature and having circular parts slidable on the magnet poles in circumferential direction, the engaging faces of the poles and armature being shaped to diminish the area of their surface engagement as the parts move circumferentially 90 from normal position.

4. The combination of a wheel body, circular separated plates arranged concentrically of the body, means for energizing the 95 plates to constitute them opposite poles of a magnet, a tread-carrying rim movable circumferentially of the body, inwardly disposed circular plates carried by the rim and overlapping and slidable on the pole-forming plates, the rim plates connected to form an armature, and the faces of said plates and poles being formed to diminish the engaging area of the magnetic force-transmitting portions thereof as the parts move circumferentially from normal position.

5. The combination of a wheel body, circular plates spaced apart and projecting outwardly from the periphery of the body, 110 means for energizing the plates to constitute them opposite poles of the magnet, a rim-carrying tread movable circumferentially of the body, plates projecting inwardly from the tread and engaging and slidable circumferentially of the pole-forming plates, the rim plates connected to form an armature, and the slidably engaging faces of the plates formed of alternative sections of magnetic and non-magnetic material with the magnetic-material face portions of the opposed plates engaging each other with such engagement diminished by relative circumferential movement of the body and rim.

6. The combination of a wheel body, separated plates projecting from the periphery thereof, means for energizing the plates to provide opposite poles of a magnet, a side face of each plate consisting of separated 120

portions of magnetic metal and interposed portions of non-magnetic metal, a tread-carrying rim having inwardly projecting circular plate-like portions overlapping the 5 pole-forming plates and slidably circumferentially on the composite faces thereof, said rim plates connected to form an armature, the pole-engaging faces of the rim plates consisting of separated portions of magnetic 10 metal and interposed portions of non-magnetic metal with the magnetic portions of the opposed plates normally engaging each other with said engagements adapted to be diminished by the relative circumferential 15 movement of the body and rim.

7. The combination of a wheel body and

a rim movable radially and circumferentially relatively to each other, a series of cushioning devices arranged around the wheel for opposing the radial movement, 20 and series of coöperating magnetic devices arranged around the wheel on the body thereof and on the rim for opposing the circumferential movement and for strengthening the said cushioning means, substan- 25 tially as described.

In testimony whereof I affix my signature in presence of two witnesses.
